FROZEN CONFECTION OR SIMILAR ARTICLE

Courtland D. Ferguson, 8100 Hampden Lane,
Bethesda, Md. 20014

Filed Sept. 8, 1969, Ser. No. 19,059

Term of patent 14 years

Int. Cl. D1—02

U.S. Cl. D1—22

FIG. 1

FIG. 3

FIG. 1 is an elevational view of a frozen confection showing my new design, the other side being substantially identical thereto.

FIG. 2 is a top plan view of the frozen confection shown in FIG. 1.

FIG. 3 is a bottom plan view thereof.

I claim:

The ornamental design for a frozen confection or similar article, substantially as shown and described.
